MERCHANDISE DISPLAY CASE

Filed Jan. 13, 1936

FIG. 2.

FIG. 1.

Edward Lee Brown
INVENTOR.

BY

Edward Lee Brown
ATTORNEY.

UNITED STATES PATENT OFFICE

104,719

DESIGN FOR A MERCHANTISE DISPLAY CASE

Edward Lee Brown, Dallas, Tex.

Application January 13, 1936, Serial No. 60,549

Term of patent 3½ years

To all whom it may concern:

Be it known that I, Edward Lee Brown, a citizen of the United States, residing at Dallas, in the county of Dallas and State of Texas, have invented a new, original, and ornamental Design for a Merchandise Display Case, of which the following is a specification, reference being had to the accompanying drawing, forming part thereof:

I claim:

The ornamental design for a merchandise display case, as shown.

EDWARD LEE BROWN.
